TIRE

Arthur E. Benson, Grosse Pointe Farms, and Vance J. Davis, Detroit, Mich., assignors to United States Rubber Company, New York, N. Y., a corporation of New Jersey

Application October 6, 1954, Serial No. 32,560

Term of patent 14 years

(Cl. D90—20)

To all whom it may concern:

Be it known that we, Arthur E. Benson and Vance J. Davis, citizens of the United States, residing at Grosse Pointe Farms, county of Wayne, and state of Michigan, and Detroit, county of Wayne, State of Michigan, respectively, have invented a new, original, and ornamental Design for a Tire, of which the following is a specification, reference being had to the accompanying drawing, forming part thereof.

Fig. 1 is an elevational view of a tire showing our design, it being understood that the design is repeated throughout the circumference of the tread of said tire;

Fig. 2 is an enlarged fragmentary perspective view of the tire showing our design; and

Fig. 3 is a partial sectional view taken substantially along the line III-III of Fig. 1.

The dominant features of our design reside in those portions shown in full lines.

We claim:

The ornamental design for a tire, substantially as shown and described.
